UNITED STATES PATENT OFFICE.

STANISLAW J. LUKASZEWSKI, OF DETROIT, MICHIGAN.

HEATER.

1,220,655.

Specification of Letters Patent. Patented Mar. 27, 1917.

Application filed July 26, 1915. Serial No. 42,083.

To all whom it may concern:

Be it known that I, STANISLAW J. LUKASZEWSKI, a citizen of the United States, residing at Detroit, in the county of Wayne and State of Michigan, have invented a new and useful Heater, of which the following is a specification.

This invention relates to water heaters in which a volatile hydro-carbon constitutes the fuel, and its object is to provide a heater which, when mounted on the chassis of an automobile, will not be extinguished by the jarring of the vehicle when in motion or by the blast of air caused by the fan, which will be strong and compact, and which can be built at comparatively low cost.

This invention consists in a heating coil and a shell for the same, a novel bottom for the shell provided with a drainage connection, a novel burner within the shell having a drain for conducting the unvolatilized fuel, a trough for receiving this liquid fuel provided with means for controlling the maximum height of the fuel therein, and a novel electric igniter for the fuel in the trough.

In the accompanying drawings, Figure 1 is a side elevation of this improved heater. Fig. 2 is a vertical central section on a plane parallel to that of Fig. 1. Fig. 3 is a plan of the head of the cylindrical shell. Fig. 4 is a section on the line 4—4 of Fig. 2, Fig. 5 is a plan of the burner. Fig. 6 is a plan of the igniter trough. Fig. 7 is a section on the line 7—7 of Fig. 6. Fig. 8 is a section on the line 8—8 of Fig. 6. Fig. 9 is a plan of the bottom of the shell. Fig. 10 is a section on the line 10—10 of Fig. 2. Fig. 11 is a section on the line 11—11 of Fig. 2. Fig. 12 is a perspective of a baffle plate.

Similar reference characters refer to like parts throughout the several views.

This heater may be used wherever water or other liquids are to be heated, but is especially adapted for heating the circulating liquid of automobile engines, as set forth in my prior Patent No. 1,007,710, dated November 7, 1911, and may be mounted in the position shown in the drawings of said patent. The present structure consists generally of a pair of heating coils and the shell therefor, a burner and its igniter, and the shell or casing for the burner.

The heating coils 1 and 2 preferably have the same number of turns, and their ends are welded, brazed or otherwise connected

into the fittings 4 and 5, as shown in Figs. 2 and 4. The shell inclosing the coils is preferably formed of the two tubular members 6 and 7, preferably of sheet steel, with the layer 8 of asbestos between them. A supply pipe 9 may screw into the fitting 4, and a discharge pipe 10, preferably in the form of a nipple, may screw into the fitting 5. A nut 12 on the nipple 10 may hold the upper ends of the coils and the fitting 5 in position, while the elbow 13 may be screwed onto the nipple outside of the nut. A nut 14 on the pipe 9 may hold the lower ends of the coils and the fitting 4 in their proper position. A window 15 of any desired character may be provided at any convenient location.

As shown in Figs. 2 and 9, the bottom of the shell is generally in the form of a hemisphere 16 having a rectangular extension 17, the lower part of which is rounded. The bottom can be secured to the shell by means of screws 18 passing through the brackets 19 into the lugs 20 at the rim of the bottom, and also by the plate 22 secured to the shell by means of the screw 23 and provided with an inturned end 24 that engages the shoulder 25 on this bottom. The rim of the bottom is formed with a groove 26 (Fig. 9) to receive the rounded end 27 of the valve body 28 of the burner, which end 27 is also mounted in a similar groove in the lower edge of the shell. By removing the screws 18 and 23, the bottom and the burner can be removed.

Fitting the upper end of the shell is a head 29 (Fig. 3) provided with downwardly extending lips 30 that fit against the interior wall of the shell, as shown in Fig. 2, a screw 32 extending through the shell into each lip. Holes 33 in the head permit the escape of products of combustion, and small pedestals 34 may be formed on the head to support cooking pots or pans a sufficient distance from the head to prevent them stopping these holes 33. A baffle 35 may be secured to the lower face of the head to prevent too rapid flow of the hot gases, and a screen 36 of fine wire gauze may be used to prevent the passage of flame from the interior of the shell.

A hood is normally mounted on the shell and consists of the body 38 having a lower flange 39 adapted to fit around the upper end of the shell, being provided with bayonet slots 40 to receive the heads of screws 32 and

be thus secured to the shell. A cylindrical band 42 is supported by the skirting 43, mounted on the body, by means of ears 44. A cap 45 has downwardly extending ears 46 that are attached to the band 42. This hood prevents the blast of air, caused by the fan just in the rear of the radiator, from passing into and down within the shell while permitting all products of combustion 10 to escape.

The burner and its igniter are mounted within the shell and are constructed as follows. (See Fig. 2). A central tube 50 has the lower end of its bore threaded to receive a nipple 51, which passes through a hole 52 in the bottom (Fig. 9) and receives a nut 53 by means of which the parts are held rigidly in position. The fuel supply pipe will be connected to this nipple. At the upper end of the nipple 51 is a ball 54 that constitutes a check valve and prevents surging of the liquid fuel in the burner. This tube 50 may be filled with filter gauze 55, if desired. At the upper end of this tube is the valve body 28 having a transverse bore 56, in which the needle valve stem 57 is mounted, the tapering valve 58 at one end controls the flow of fuel from the passage 59. A bearing 60 for the stem is fastened in the outer end of the valve body, and a disk 62 having radial teeth may be mounted on the outer end of this bearing. A handle 63 is secured to the stem 57 and provided with a resilient detent 64 that engages the teeth on the disk 62 and thus prevents the stem from being turned through the jarring of the vehicle on which the heater is mounted.

A U-shaped mixing tube has parallel arms 65 and 66, one above the other, the lower 40 being in alignment with the fuel discharge passage 59. The upper arm is fitted in an opening in the outer shell 67 of the burner proper, the upper portion of which is curved inwardly to form a burner ring 68 provided with slits 69 through which may pass the volatilized fuel and the air mixed therewith. A frusto-conical thimble 71 fits within this ring at its upper end and has a radial flange 72 that extends across the end of the shell 67 to complete the fuel chamber. A few small holes 73 in this thimble 71 in line with the arm 65 of the mixing tube permit a small amount of the fuel vapor to pass into the space around the stem 74. The U-tube, 55 shell and thimble may be secured together as shown in Fig. 5. On the lower end of the tube 50 is a trough 75, held in position by means of screws 76, shown in Fig. 6. In the central raised portion 77 of the trough 60 is formed a small hole 78 for one of the ignition points 79. In the trough is a small vertical passage 80 that determines the height of the liquid in the trough. An arm 82 on the trough supports a small spark plug 83 having an ignition point 84. A tube 85

of any desirable insulating material carries a connector 86 that joins to the spark plug by means of a wire 87 and to an engaging clamp 88 by means of the wire 89.

Mounted on the central raised portion of the trough is a perforated thimble 91, air passing up through the center of the trough into this thimble and then laterally outward. An annular plate 92, substantially U shaped in cross-section, confines the flame and also 75 supplies it with air. A baffle plate 93 secured to the nozzle 94 by means of nuts 95 prevents the flame of the burning liquid in the trough from igniting the fuel that flows from the orifice 59. The bottom of the arm 80 66 of the mixing tube is so formed as to drain to the short pipe 96 that discharges into the trough 75.

Secured to the rectangular extension 17 of the bottom and to the shell of the heater 85 is an air chamber having sides 100, 101 and 102. Its cover 103 is mounted on the bracket 104 carried by the side 102 and on the shell, at such a distance above the air chamber that the flange or skirting 106 of this cover 90 extends only a slight distance below the upper edge of the chamber. This cover is formed with perforations 105 to permit the escape of the excess of air which enters below the flange 106.

A baffle plate 107 having ears 109 may be connected to the cover, as shown in Figs. 2, 10 and 11. A plate 108 (Fig. 4) may be secured to extend between the walls 100 and 101, forming an air space between the air 100 chamber and the shell of the heater. The walls 100 and 101 are shown formed with air holes 110. The operation of this device is as follows:

The heater coils 1 and 2 are always full 105 of the liquid to be heated. When the operation of the heater is desired, the handle 63 is turned back to slightly open the orifice 59. This will permit fuel to be forced from this orifice and flow across into the lower arm 66 of the mixing tube, thence down the pipe 96 into the trough 75. The clamp 88 is then connected to a spark plug of the engine or to any other source of a proper current, which causes a spark to jump across 110 from one of the points 79-84 to the other, which ignites the liquid in the trough. The flame from this liquid passes up around the tube 50 and heats the valve body 28 and soon volatilizes the liquid fuel. When volatilized, the fuel will mix with air in the mixing tube and pass into the ring 67 and out through the small holes 73 and the slits 69. The flame from the trough 75 will ignite the fuel vapor, which will burn at these holes 115 and slits, the flame at the holes 73 heating the stem 74 and thereby the body 28 after the flame in the trough 75 is extinguished because of lack of fuel.

Should the fuel in the trough 75 accumulate 120

too rapidly, it will flow off through the passage 80 into the trough 112 in the bottom 16, and may then be drained away by means of the pipe 113. As this heater is especially intended for use on automobiles which are usually kept for comparatively long periods of time in cold garages, it is often desirable to keep the heater in operation during the entire time the vehicle is thus stored. In

10 order to prevent the flame of the heater from igniting any fumes of the hydrocarbon fuel that may be spilled on the floor, the screens 36 and 111 are provided and are of such fineness that a flame cannot pass 15 through them, thus rendering a fire because of the use of this heater impossible.

It is often desirable to keep the heater in operation while the automobile is moving from place to place, especially when the vehicle is used for delivering goods or for soliciting orders. In such case, and on very windy days, strong blasts of air pass around the heater which would affect the flame unless proper baffle plates were employed. By 25 using a cover 103 having a flange 106 extending down below the upper edge of the air chamber, and by mounting a baffle plate 107 as shown, the flow of air into the chamber is greatly impeded.

30 As automobiles are constantly growing in favor for picnic purposes, the hood of this heater is made removable so that cooking utensils may be placed over the head 29, and food can then be heated while the engine is 35 kept warm.

Many changes in the details and proportions of my construction may be made by those skilled in the art without departing 40 from the spirit of my invention as set forth in the annexed claims.

I claim:

1. In a hydro-carbon burner, the combination of a valve body having a horizontal fuel discharge orifice, a valve within the valve 45 body to control the flow of fuel, a burner ring mounted on said body, a U-shaped mixing tube having its arms in the same vertical plane with the upper arm connected into said burner ring and its lower arm in alinement with but spaced apart from said fuel orifice, a trough mounted below the valve body, means to conduct fuel thereto from the mixing tube, electric means to ignite said fuel, and a shield mounted below and extending across between said fuel orifice and the inlet end of the mixing tube to prevent the flame from the trough igniting the fuel at said orifice.

2. In a hydro-carbon burner, the combination of a valve body having a horizontal fuel discharge orifice, a valve within the valve body to control the flow of fuel, a U-shaped mixing tube having one arm in alinement with but spaced apart from said fuel orifice, 50 a burner ring at the end of the other arm of

said mixing tube, a fuel trough below said valve body, a tube to convey unvaporized fuel from the mixing tube to said trough, means to ignite the fuel in said trough, and means mounted below the mixing tube and 70 the discharge orifice in the valve body and extending across the space between them to prevent the flame from the trough igniting the fuel at said orifice.

3. In a hydro-carbon burner, the combination of a valve body having a horizontal fuel discharge orifice, a tube to feed fuel thereto, a valve to control the flow of fuel from said discharge orifice, a burner ring above said body, a U-shaped mixing tube having one 75 arm connected into said burner ring and the other arm adjacent to but spaced apart from the fuel orifice, said mixing tube having a depressed portion adjacent its inlet opening, a fuel trough below the valve body, a drain 80 pipe leading from the depressed portion of the mixing tube to said trough, an electric igniter mounted adjacent to said trough, and means mounted below the mixing tube and the discharge orifice in the valve body 85 and extending across the space between them to prevent the flame from the trough igniting the fuel at said orifice.

4. In a hydro-carbon burner, the combination of a valve body having a horizontal fuel discharge orifice, a valve within the valve body to control the flow of fuel, a U-shaped mixing tube having one arm in alinement with but spaced apart from said fuel orifice, 90 a burner ring at the end of the other arm of said mixing tube, a fuel trough below said valve body, a tube to convey unvaporized fuel from the mixing tube to said trough, means to ignite the fuel in said trough, and means mounted below the mixing tube and the discharge orifice in the valve body 95 and extending across the space between them to prevent the flame from the trough igniting the fuel at said orifice.

5. In a hydro-carbon burner, the combination of a valve body having a fuel discharge 100 orifice, a valve within the valve body to control the flow of fuel, a tube to feed fuel thereto, a burner ring, a mixing tube having its outlet end connected into the burner ring and its inlet end adjacent to but spaced 105 apart from the discharge orifice of the valve body, said mixing tube being formed with a depressed portion adjacent its inlet end, a trough mounted below the valve body, a tube to convey liquid fuel from said depressed portion of the mixing tube to said trough, means to ignite the fuel in the trough, and means to prevent the flame from the trough igniting the fuel at said orifice.

6. A burner comprising a valve body having a horizontal discharge orifice, a valve within the valve body to control the flow of fuel, a slotted burner ring mounted above the valve body, a U-shaped mixing tube having 110

- its arms in a vertical plane with one arm connected into said burner ring and the other in alinement with said orifice, a fuel tube connected to the valve body, a fuel trough below the valve body, a drain pipe leading from the mixing tube to the trough, means to control the level of fuel in the trough, and an electric igniter mounted adjacent said trough.
- 10 7. A burner comprising a valve body having a horizontal discharge orifice, a valve within the valve body to control the flow of fuel, a slitted burner ring mounted above the valve body, a U-shaped mixing tube having its arms in a vertical plane with one arm connected into said burner ring and the other in alinement with said orifice, a fuel tube connected to the valve body, an annular fuel trough below said valve body, a perforated 20 cap mounted in the middle of the trough which is formed with passages to supply air

to said cap, a drain pipe leading from the mixing tube to the trough, and an electric igniter mounted adjacent said trough.

8. A burner comprising a valve body having a horizontal discharge orifice, a valve within the valve body to control the flow of fuel, a slitted burner ring mounted above the valve body, a U-shaped mixing tube having its arms in a vertical plane with one arm 25 connected into said burner ring and the other in alinement with said orifice, a fuel tube connected to the valve body, a fuel trough below the valve body, a drain pipe leading from the mixing tube to the trough, 30 and an electric igniter mounted adjacent said trough, said trough being formed with an overflow passage to predetermine the maximum height of fuel in the trough.

In testimony whereof I sign this specification.

STANISLAW J. LUKASZEWSKI.
